UNITED STATES PATENT OFFICE.

ALFRED E. STRINGER, OF CHICAGO, ILLINOIS.

CLOSET-BOWL AND COVER MOUNT.

1,212,280.

Specification of Letters Patent. Patented Jan. 16, 1917.

Application filed November 22, 1913. Serial No. 802,343.

To all whom it may concern:

Be it known that I, ALFRED E. STRINGER, a citizen of the United States, and a resident of the city of Chicago, county of Cook, and State of Illinois, have invented certain new and useful Improvements in Closet-Bowl and Cover Mounts; and I do hereby declare that the following is a full, clear, and exact description of the same, reference being had to the accompanying drawings, and to the numerals of reference marked thereon, which form a part of this specification.

As heretofore constructed, wall attached toilet closet bowls have been difficult to install, and the installation has not always proved reliable. In most constructions the bowl is supported upon the wall or marble slab affording the wall of the closet or partly thereon, and the soil pipe which is connected with a horn on the bowl, is frequently so connected as to exert stress on the bowl with the result of breaking the same. Furthermore, in such constructions heretofore, the utmost nicety and exactness of fitting is required to enable the connection to be made between the soil pipe and the bowl at all, and any stress as applied to the bowl is communicated more or less directly to the joint between the same and the soil pipe, with the effect of soon producing a leak. In most constructions, the seat cover has been mounted upon the bowl so that whether open or closed, it becomes more or less difficult to properly clean the bowl, due to the projection of the various attaching means for the cover.

By my invention a mounting is provided for the bowl and cover therefor, such that the same are retained against the wall, and suitable supporting means is provided to relieve the soil pipe of any stress thereon.

It is an object of this invention to provide a mounting for closet bowls wherein the soil pipe and the bowl are each supported against the wall to maintain the same in register without stress existing therebetween, and such attaching means also serving to afford a support for the seat and cover for the bowl without imposing the weight of the bowl on the wall.

It is also an object of this invention to provide a device wherein a soil pipe and closet bowl are supported in register with one another, with an adjustable packing gland engaging therearound to maintain a

seal therebetween, and with adjustable spacing elements between the bowl and the support therefor to relieve the wall of stress.

It is also an object of this invention to provide a mount adapted to support a closet bowl and soil pipe in register with one another, the attaching means for which afford a hinged support for a seat and cover for said bowl whereby the wall or like is entirely relieved of the weight of the bowl.

It is also an object of this invention to provide a device wherein the attaching means for the bowl and soil pipe afford a hinged support for the seat and cover of the bowl, said attaching means being capable of adjustment to insure a finished appearance and a complete inclosure of the adjusting members when said seat and cover are attached in proper position.

It is furthermore an object of this invention to provide an adjustable hinged mounting for the seat and cover of a closet bowl whereby the attaching bolts for said closet bowl to the wall may be utilized in supporting the seat and cover in proper position above said bowl.

It is finally an object of this invention to provide a device consisting of few parts and of simple construction adapted to properly support a closet bowl and the seat and cover therefor in proper relation upon a wall, and without exerting stress upon the soil pipe to which the same is connected.

The invention (in a preferred form) is illustrated in the drawings, and hereinafter more fully described.

In the drawings: Figure 1 is a central vertical section of a closet bowl, showing the same attached to a wall by means embodying the principles of my invention. Fig. 2 is a section taken on line 2-2 of Fig. 1. Fig. 3 is a section taken on line 3-3 of Fig. 1. Fig. 4 is a section taken on line 4-4 of Fig. 1. Fig. 5 is a section taken on line 5-5 of Fig. 4.

As shown in the drawings: the reference numeral 1, indicates a closet bowl having an attaching plate 2, integral therewith, and adapted to abut against a wall 3, for supporting the closet bowl thereon. A soil pipe 4, is shown projecting through an aperture in said wall 3, and registering with the soil extension 5, of the closet bowl. The attaching plate 2, of the closet bowl, is substantially of triangular outline, and is adapted to coöp-

erate with a triangular spider 6, the feet 7, of which are apertured to register with apertures in said attaching plate 2, to permit the insertion therethrough of attaching bolts, although, of course, the particular shape of the spider or attaching plate is immaterial. A split clamping ring 6^a, forms a part of said spider and is adapted to engage around and support the soil pipe 4. One bolt 8, is adapted to thread into one of said spider feet 7, and the plate is tightened thereon by means of a nut 9, and a larger ornamental nut 10, inclosing the same, and bearing upon the outer surface of said plate 2, although the latter nut is not essential.

For the purpose of maintaining a seal between the soil pipe 4, and the soil extension 5, of the closet bowl, a packing ring or gasket 11, is provided surrounding the junction of the two pipe extensions, and a sliding compression ring 12, surrounds said soil pipe 4, and is impelled against said packing 11, by a thrust ring 13, which is adapted to be drawn toward said junction of said pipe by means of adjusting bolts 14 and nuts 14^a, the latter upon being tightened acting to draw up the respective bolts. A packing ring 15, is also provided between said compression ring 12, and said thrust ring 13, in order to insure a seal between the co-operating elements of the gland. An adjustable supporting leg 16, has threaded engagement with a lug 16^a, on the lower leg of the spider 6, so that by turning the same the spider 35 may be thrust upwardly to entirely relieve the wall of the weight of the bowl and accessories.

The upper portion of the bowl is supported by means of bolts 17, engaging through said attaching plate 2, the wall 3, and the upper feet 7, of the spider 6. In order to relieve the wall 3, which is usually a marble slab, of any stress whatsoever, complementally threaded spacing nuts denoted respectively as 17^a, and 17^b, are provided, the nut 17^a, being slidably mounted on the bolts 8 and 17, respectively, so that by adjusting the respective nuts 17^a, and 17^b, the supporting stress from the attaching plate 2, is transmitted through the spacing nuts directly to the spider elements 7. Said bolts 17, are each provided with an enlarged ornamental head 18, which is apertured and internally threaded as shown clearly in Fig. 5, to receive therein hinge studs or pintles 19, which, due to the threaded engagement thereof are adjustable therein. A locking screw 20, having a spherical head conforming to the contour of the head 18, is threaded into the inner end of each of said hinge pintles 19.

It may be readily seen from Fig. 5, that the pintle studs 19, may be each independently adjusted relative the respective bolt heads 18, and locked in such adjusted posi-

tion by means of the screw, the elements in all positions affording a finished appearance to the assembled device.

As shown in Fig. 5, said pintles 19, are shown in an extreme inner position, the same being adjustable outwardly by loosening the screw 20, to thus provide a hinged connection wherein in the mounting of said bolts 17, the distance is greater than that shown in the drawings.

Journalized on the narrowed inwardly projecting ends of said pintle studs is a hinge member 21, adapted to be connected upon the seat for the closet bowl. Immediately adjacent thereto, and upon the slightly enlarged portion of said stud shaft is a seat cover hinge member or leaf 22, which is, of course, independently operable with respect to said hinge portion 21. Thus the bolts 17, not only serve to afford a hinge connection for the seat and cover of the closet bowl, but also co-operate, inasmuch as they extend through the attaching plate 2, of said bowl, and thread into the upwardly directed feet 7, of the spider 6, to assist in supporting the closet bowl upon the wall. A cover 23, may be attached to the hinge members or leaf 22, in any suitable manner, and serves to close over the seat 24, attached to the hinge member 21, as is usual in such constructions.

The operation is as follows: When it is desired to mount the closet bowl upon the wall, the wall is apertured at a plurality of points corresponding to the position of the apertures in the feet of the supporting spider 6, and the closet bowl is then positioned with the apertures in the attaching plate 2, in register with said wall apertures, and the respective bolts 8, 14, and 17, are inserted therethrough. Of course, the packing gland element must have been previously inserted over the soil pipe 4, and after the bowl is properly mounted the gland is tightened from the front face of the attaching plate 2, by drawing up the bolts 14, which project therethrough. It is evident that particular conditions may determine the distance between the upper feet 7, of the spider, that is to say the same may vary, and, of course, a bowl must be provided with apertures adapted to register therewith, but the hinged connection which is afforded by the enlarged head of the upper attaching bolts, is adjustable to compensate for the variation in distance between the same, as already described and clearly shown in Figs. 4, and 5. I am aware that various details of construction may be varied through a wide range without departing from the principles of this invention. I therefore do not purpose limiting the patent granted other wise than necessitated by the prior art.

I claim as my invention:

1. In a device of the class described at

taching bolts having apertured internally threaded heads thereon, short stud shafts adjustably and rigidly secured transversely in the heads of each of said bolts, the outer ends of said stud shafts reduced in diameter, a hinge member fitted on the reduced ends of said stud shafts, and independent hinge members, one each secured upon said stud shafts and held from longitudinal movement thereon by said first mentioned hinge member.

2. In a hinge construction for seat and cover members of a closet bowl, attaching bolts adapted to secure the closet bowl upon a wall, hinge pintles secured adjustably and transversely in the heads of said attaching bolts and projecting toward one another in alinement, means projecting through an aperture in the heads of said attaching bolts and threading into said hinge pintles to clamp the same rigidly in said heads of said bolts, independent hinge members pivotally journaled on said hinge pintles, and a single hinge member journaled on both of the inner ends of said hinge pintles.

3. In a device of the class described in combination with a closet bowl, of a pair of attaching bolts for the bowl having apertured heads, hinge pintle members threaded into said apertures, locking screws threaded in said hinge pintle members and adapted to bear on the heads of the attaching bolts to retain the pintles in their adjusted position, and seat and cover hinge members or leaves journaled upon the hinge pintle members.

4. In an adjustable hinge member for cover and seat members of a closet bowl, a pair of attaching heads secured to the bowl, hinge pintles secured to the attaching heads, said pintles being capable of a lateral adjustment with respect to each other, means coöperating with the pintles and the attaching heads for positively retaining the pintles in their adjusted position, a hinge member slidably secured to each of the pintles and extending therebetween, a plurality of hinge leaves, one each journaled on said pintles and one carried by said hinge member.

5. In an adjustable hinge member for a cover and seat member of a closet bowl, attaching bolts adapted to secure the closet bowl upon the wall, pintles having threaded connections with the attaching bolts, said pintles being capable of a lateral adjustment with respect to each other, means coöperating with the pintles and in engagement with the attaching bolts for positively retaining the pintles in their adjusted positions, an open ended hinge member adapted to fit over the ends of the hinge pintles and slidably connected therewith, a plurality of hinge leaves, one each journaled on said pin-

ties, and one carried by the open ended hinge member.

6. In an adjustable hinge member for cover and seat members of a closet bowl, apertured bolts adapted to secure the closet bowl upon the wall, pintles having threaded connections with the attaching bolts whereby a lateral adjustment thereof is permitted, the said pintles having threaded interior sockets therein, locking screws passing through the attaching heads and entering the threaded sockets in the pintles for positively holding the pintles in adjusted position, a hinge member supported by said pintles, and hinged leaves or members journaled on the first mentioned pintles and hinge member for supporting the seat and cover respectively.

7. A device of the class described, comprising attaching bolts having openings in the heads thereof, a pintle adjustably secured in the head of each of said bolts, a hinge member having openings at each end adapted to receive the outer portions of the hinge pintles, and permit the adjustment of said pintles, and hinge leaves journaled on the hinge pintles and carried by the hinge member for supporting the seat and cover respectively.

8. In an adjustable hinge mounting for cover and seat members of a closet bowl, a pair of attaching heads secured to the bowl, the said heads having transverse apertures therethrough, pintles having threaded connections with the heads entering the apertures therein, means for adjusting said pintles laterally with respect to each other comprising locking screws passing through the transverse apertures in the attaching heads and engaging said pintles, the locking screws being provided with portions adapted to bear on the attaching heads and inclose one end of the transverse apertures passing therethrough, a hinge member supported by said pintles, hinge leaves journaled on the pintles and a hinge leaf carried by the hinge member for supporting the seat and hinge cover respectively.

9. In an adjustable hinge mounting for cover and seat members a pair of attaching heads secured to the bowl, hinge pintles adjustably secured to the heads, a hollow hinge member extending between the pintles adapted to receive the ends of the said pintles, the said pintles being adjustable laterally with respect to each other and the attaching heads means for retaining the pintles in their adjusted position, and a plurality of hinge leaves one each journaled on said pintles and one carried by the hinge member.

10. A device of the class described comprising attaching members, pintles adjustably secured to said members, an adjustable hinge member adapted to be supported by

5 said pintles and positioned therebetween, said pintles being capable of a lateral adjustment with respect to the attaching members, and a cover supporting means carried by said hinge member for supporting and positioning a cover.

10 11. A device of the class described comprising attaching members, adjustable pintles carried thereby and capable of a lateral adjustment with respect to the attaching members, and seat supporting devices carried by said pintles and adapted to be adjusted thereby for supporting and positioning a seat relative to the bowl, substantially 15 as described.

12. A device of the class described comprising attaching members having openings in the heads thereof, pintles adjustably secured in said heads, a hinge member adapted 20 to be supported by said pintles and the pintles being adjustable laterally with respect to the attaching members to correspondingly

adjust said hinge member, and a cover supporting means carried by said hinge member for supporting and positioning a cover. 25

13. A device of the class described comprising attaching members having openings in the heads thereof, pintles adjustably secured in said heads, a hinge member adapted to be supported by said pintles and the pintles being adjustable laterally with respect to the attaching means to correspondingly adjust said hinge member and seat, and cover supporting means carried by said hinge member and said hinge pintles for 30 supporting and positioning a seat and cover. 35

In testimony whereof I have hereunto subscribed my name in the presence of two subscribing witnesses.

ALFRED E. STRINGER.
